A. T. LONG

TRUNK LOCK

Filed March 9, 1926

UNITED STATES PATENT OFFICE.

ALLEN T. LONG, OF PETERSBURG, VIRGINIA, ASSIGNOR TO ATKINSON & LONG MFG. CO., OF PETERSBURG, VIRGINIA, A CORPORATION OF NEW JERSEY.

TRUNK LOCK.

Application filed March 9, 1926. Serial No. 93,500.

This invention relates to trunk locks and particularly to that class of trunk locks having a recess to receive the upper end of the hasp, and wherein the hasp is hinged to the lower section of the trunk and carries at its upper end a lock casing adapted to be received in the cup or recess of the base plate and engaged therewith by lock bolts.

These locks as ordinarily constructed are weak at the point of hinge connection between the hasp and the base section which is attached to the lower section of the trunk, for the reason that the hasp is not braced against lateral oscillation or lateral movement with relation to the base plate on the lid of the trunk and one of the objects of my invention is to provide means for bracing the hasp against any lateral movement when the trunk is closed and when the lock is closed so that the base plate on the lid of the trunk and the hasp act practically under these conditions, as a solid or rigid member having no relative lateral play.

A further object of my invention is to provide a lock of this character in which the cup receiving the lock proper carried upon the hasp, is formed integral with the base plate as distinguished from being attached to the base plate and, therefore, relatively weak.

A still further object is to so construct this cup as to provide recesses or keepers within which the bolt or bolts are received, which keepers will not act to unduly weaken the cup.

Another object is to so form the hasp immediately surrounding the keyhole of the hasp that the combinations of trunk locks may be varied without changing the tumblers of the locks.

Other objects will appear in the course of the following description.

My invention is illustrated in the accompanying drawings wherein:—

Figure 1 is a front elevation of a trunk lock constructed in accordance with my invention;

Fig. 2 is a rear elevation of the base plate;

Fig. 3 is a section on the line 3—3 of Figure 2;

Fig. 4 is a rear elevation of the hasp; Fig. 5 is an elevation of the lock carrying plate;

Fig. 6 is a section through the head of the hasp.

Referring to these drawings it will be seen that the portion of the lock which is attached to the lid of the trunk comprises a base plate 10. This is preferably stamped from a sheet of metal to provide the circular cup 11, and outward of this cup the concentric outwardly bulging rib 12 which extends nearly around the cup but terminates in two vertically disposed hollow ribs 13 extending downward parallel to each other, these ribs being carried down below the lower end of the plate, as at 14. It will be noted that these portions 14 are slightly depressed relative to the outer faces or the portions 13 of the rib. The cup 11 at diametrically opposite points is formed with slits 15 and the material below these slits is forced outward as at 16, see Figure 3, so that the upper walls of these slits 15 constitute keepers with which the bolts of the lock are adapted to engage.

The hasp consists of the base plate 17 and the tongue 18. This tongue has a circular head 19 and is made of relatively thin metal defined by an inwardly extending flange 20, the face of the head being slightly depressed as at 21, and the central portion of the head being annularly depressed as at 22, and formed with a central opening 23 having a radial extension at one point. This portion 22, therefore, constitutes a key ward as will appear hereafter.

The base plate 17 for the tongue 18 is of stamped metal to provide a nearly annular rib 24, the extremities of which terminate in parallel portions 25 which are adapted to receive the portions 14 when the lid of the trunk is closed. The central portion of the base plate 17 is embossed in any desired manner to strengthen it or make it more or less ornamental and exteriorly of the hollow rib 24 the base plate 17 is formed with apertures for the passage of rivets whereby the base plate is held to the body of the trunk. The tongue 18 is connected

to the base plate by means of a U-shaped yoke 26 and the base plate is formed with a re-bent tongue 27 to form a bead disposed between the ends of the yoke 26. The ends of the yoke 26 are formed with eyes and a pintle 28 extends through the bead formed by the re-bent tongue 27 and through these eyes. Thus the tongue 18 of the hasp is hingedly connected to the base plate of the hasp.

Disposed against the inside face of the head 19 is a cup-shaped lock casing 29, see Figure 5, which is riveted to the head 19 at a plurality of points, this lock casing having the laterally projectible spring pressed bolts 30 ordinarily found in trunk locks of this character, and a barrel 31 which through tumblers disposed within the casing, acts to retract the bolts 30 when the barrel is rotated by means of the key 33 inserted in the slot 32 of the barrel. A face plate 34 is riveted to the outer face of the head 19 of the hasp, this face plate having a central outwardly bulging portion formed with a central opening within which the barrel 31 operates.

It will be noted, of course, that the slot 32 is adapted to align, when in one position, with the extension 23^a of the central aperture 23. The annular depression of ward 22 coacts with the key 33 in a manner which will be later stated.

It will be seen from Figure 1 that when the hasp is in engagement with its keeper 35 that the tongue 18 lies between the projecting rib portions 13 and the head lies within the annular ribbed portion 12 and that the extensions 14 of the ribbed portions 13 extend down beyond the hinge for the hasp so that under these circumstances any lateral movement of the base plate 17 and the hasp with relation to the base plate 10 is absolutely prevented or reduced to an extremely small amount so that the lateral wrenching action which tends to damage the ordinary trunk lock is not present in my improved construction, and thus when the lock is closed, the lid and the body of the trunk are held from relative lateral movement. When the head 19 of the hasp is inserted within the cup 11 the bolts 30 will spring into place behind the outer walls of the slots 15 thus locking the hasp and the plate 10 or keeper together.

As will be seen from Figure 6 the head 19 with its opening 23 is disposed inward of the face plate 34 and the margins 22 of the opening 23 constitute a ward and unless the key 33 is fitted to pass this ward the key cannot be turned and thus it will be obvious that by having this portion 22 disposed at different distances from the face plate 34, that wards located at different distances from the face plate 34 are provided and thus one va-

riable element in the lock is provided which, with the variations in the disposition of the regular wards, will permit a large number of different combinations to be made. Thus on one lot of locks the rim or margin 22 will be forced inward to a certain depth and on another lot of locks this portion 22 may be forced further inward. In another set of locks this portion 22 may be forced outward or nearer to the face plate 34 and in still another set of locks this plate 34 will be disposed in the plane of the metal forming the head. Thus, by varying the distances of this portion 22 from the plate 34, various combinations may be made which will very greatly vary the combinations capable with locks having the same tumbler arrangement. Thus, in Figure 6 I have illustrated the portion 22 as being slightly pressed inward and the key 33 as being formed with a bit, cut away at 35. Unless this ward 22 fits this recess 35 the key will not operate within the lock though the bit of the key is properly notched to fit the tumblers.

It will be seen that I have provided a trunk lock which may be stamped up out of sheet metal, which may be cheaply constructed and yet which is thoroughly strong and rigid in actual use. Furthermore I have provided a lock, the combination of which is easily changed by the disposition of the ward formed by the portion 22 and that further in this improved lock the cup, which constitutes the keeper, is integral with the keeper base plate so that a much stronger and cheaper construction is provided than heretofore where the cup was a separate stamping and attached by lugs inserted through slots in the base plate and over-turned thereon.

While I have illustrated a certain particular design of trunk lock with certain detailed features of construction and arrangement of parts I do not wish to be limited thereto as it is obvious that many changes might be made therein without departing from the spirit of the invention as defined in the appended claims.

In the foregoing description, and in some of the appended claims, I refer to the hasp as being vertically positioned in use, and to the "lid" of the trunk, inferring that the lock herein disclosed is used with what is known in the trade as a "general service" trunk. This is done, however, merely for convenience of description, and it is of course to be understood that my improved lock is equally applicable to wardrobe trunks, in connection with which the lock will be horizontally disposed and the hasp and base plate carried by the respective trunk sections, instead of "lower section" and "lid".

I claim:

1. In a trunk lock, a keeper plate having

a lock receiving cup pressed out therefrom and having portions of its side walls pressed outward to provide keepers with which the bolt of a lock may engage.

5 2. In a trunk lock, a keeper plate having a lock receiving cup pressed out therefrom, the side wall of the cup being slit at op-

posite points, the wall inward of the slit being forced outward to thereby provide keepers with which the bolts of a lock are 10 adapted to engage.

In testimony whereof I hereunto affix my signature.

ALLEN T. LONG.
